UNITED STATES PATENT OFFICE

2,594,418

SALICYLIC ACID SALT OF 8-(5'-ISOPROPYLAMINOAMYLAMINO)-6-METHOXYQUINOLINE

Charles F. Geschickter, Rock Creek Hills, and
Martin I. Rubin, Silver Spring, Md., assignors
to Geschickter Fund for Medical Research, Inc.,
New York, N. Y., a corporation of New York

No Drawing. Application September 30, 1949,
Serial No. 118,997

1 Claim. (Cl. 260—286)

1

The present invention relates to a new therapeutic agent. More particularly the present invention relates to a new antihistamine especially effective on allergic diseases affecting the respiratory tract.

The antihistamines in current use have not proven to be entirely effective in the control of many cases of asthma and non-seasonal rhinitis. Where effective, they afford symptomatic rather than permanent relief or cure. The same is true of desensitizing injections of protein substances which have the added disadvantage of requiring elaborate intradermal testing to determine the nature of the sensitizing agent or allergen.

In accordance with the present invention certain new antihistamine substances have been found which concentrate especially in the respiratory epithelium and which had a prolonged duration so that a serum level could be established and maintained. The particular antihistamines which are the subject of the present invention are amino-quinolines and in particular the mono-salicylates of 6 methoxy 8 substituted quinolines. The particular salicylates involved are the mono-salicylates of compounds represented by the following formula:

wherein R is a poly methylene chain of from 2 to 6 carbon atoms and R₁ is an alkyl radical of from 2 to 6 carbon atoms. An especially desirable compound was the mono-salicylate of 8-(5'-isopropylaminoamylamino)-6-methoxyquinoline. This compound was administered to a number of patients and it was found that plasma levels as high as .1 mg. per liter could be obtained on daily doses as low as 60 mg. In addition the compound showed 90% retention on a daily dose in the tissue and body fluids with a high concentration in the respiratory tissue. It was found to have excellent results in various types of allergy and common cold and in cases of chronic sinusitis. Undesirable side effects were not noticeable in substantially all cases.

The salicylate salt was prepared by boiling the

4 gs. of 8-(5'-isopropylaminoamylamino)-6-methoxyquinoline were boiled for 15 minutes with a solution of 5 gs. of salicylic acid in 20 cc. of ethanol, concentrated to dryness and extracted 20 with 3 portions of hot (70-90° C.) boiling petroleum ether. The hot petroleum ether solution was decanted and the residue dried. The residue was then suitably formed into 15 mg. 10 capsules.

The following specific example serves to illustrate the present invention, but is not intended to limit the same:

Example I

15 4 gs. of 8-(5'-isopropylaminoamylamino)-6-methoxyquinoline were boiled for 15 minutes with a solution of 5 gs. of salicylic acid in 20 cc. of ethanol, concentrated to dryness and extracted 20 with 3 portions of hot (70-90° C.) boiling petroleum ether. The hot petroleum ether solution was decanted and the residue showed the correct elementary values for the salicylate salt.

It will be obvious to those skilled in the art 25 that various changes may be made without departing from the spirit of the invention and therefore the invention is not limited to what is described in the specification but only as indicated in the appended claim.

30 What is claimed is:

A new compound consisting of the salicylic acid salt of 8-(5'-isopropylaminoamylamino)-6-methoxyquinoline.

CHARLES F. GESCHICKTER.
